UNITED STATES PATENT OFFICE.

ARTHUR DAVIS, OF KIDDERMINSTER, ENGLAND, ASSIGNOR TO THOMAS BOND WORTH & SONS LIMITED, OF STOURPORT, ENGLAND.

LOOM FOR WEAVING TUFTED FABRICS, SUCH AS CARPETS AND THE LIKE.

1,341,417.

Specification of Letters Patent.

Patented May 25, 1920.

Application filed June 6, 1916. Serial No. 102,075.

To all whom it may concern:

Be it known that I, ARTHUR DAVIS, a subject of the King of Great Britain and Ireland, residing at 62 Woodfield Crescent, Kidderminster, in the county of Worcester, England, have invented new and useful Improvements Relating to Looms for Weaving Tufted Fabrics, Such as Carpets and the like, of which the following is a specification.

10 This invention relates to looms for fabrics of the kind in which the pile forming yarns or tufts are inserted between the warp threads and are then bound in after being doubled around the desired weft thread or 15 threads.

My present improvements enable a weave of the above kind to be obtained with a fewer number of movements than heretofore, and with a very appreciable saving in the time of 20 working, owing to the several motions, some of them concurrent, being so timed among themselves, as to utilize the main cams to the fullest degree.

The present invention therefore aims not 25 only at simplicity in the machinery, with a proportionate saving of expense and trouble, but chiefly at increasing the output of the loom without impairing its smoothness in action, so that there is no additional wear 30 and tear, in spite of the increase in speed.

In order to carry out these objects, I have devised certain means whereby the whole of 35 the weft shots required for one row of tufts, whether in a two, three or four shot weave, are produced by one single insertion and withdrawal across the warp threads of two weft-carrying needles simultaneously, such wefts being placed during the same time in suitable position for the insertion of the tuft 40 yarns as hereinafter described.

The weft-carrying needles may be of the type in which the eyes are completely surrounded, or else the eyes (or either of them) may be of the type usually termed slip eyes.

45 Before each insertion of the weft needles and wefts, the warp threads are inclined by suitable mechanism to form sheds above and below the stuffer or dead warp, which is kept in a horizontal position or thereabout. The 50 weft-carrying needles enter the sheds so formed, one needle above the dead warp and the other below same until their eyes reach the opposite side of the loom, when two small shuttles containing selvage threads are 55 passed simultaneously through (or if desired

only into) the loops or beads in the wefts at the finish of the insertion and as the needles are in the act of being withdrawn.

For the insertion of the tufts, in cases where a three shot weave is being woven, the 60 weft thread in the lower shed and a portion of the weft thread in the upper shed is moved forward to the fell of the fabric by a device at the edges of the fabric, the remaining portion of the weft thread in the upper shed 65 being suitably held back in position at the shuttle side of the fabric. I may for instance, hold this portion back by means of the shuttle itself, a special lever or finger (termed herein a placer) serving to carry or 70 push the other portion forward toward the comb.

When the needles have been withdrawn out of the sheds, the inclined warp threads are conveniently brought to a more horizontal position. The tuft yarns are then inserted through the warp and between the wefts; the sheds are again formed and kept 75 open as much as may be desired, and that portion of the weft which has been held back 80 behind the tuft yarns is pulled taut or closed up by the selvage motion. The slay then beats up the wefts and tuft yarns close together at the fell, and the warp threads are brought to their horizontal position or thereabout. The slay now moves toward the back 85 position, and the comb or under reed or the like brings up the tufts.

The tufts having been cut, the sheds are re-formed in reverse position for another 90 insertion of wefts and tufts in similar order as described, the comb first falling to allow the wefts and tufts to be beaten up.

A two shot weave could be made with 95 only a slight modification of the mechanism as disclosed in Figures 10 and 11.

For a three shot weave, the upper needle is preferably supplied with a double or extra quantity of weft of the required count or weight from one or more cops or 100 balls of weft material, and the other needle with the usual quantity of weft from one cop or ball of weft material, but if the quantities in each needle are uniform, the weave may still be a satisfactory one, although one set of wefts will then differ 105 in substance from the other.

For a four shot weave, each needle may be supplied as desired, with weft from one or more cops or balls of weft material. 110

We can obtain four shot weave in a similar manner and by similar means to what has been above described, the only alteration being that the upper and lower shots 5 of weft are both divided for the insertion of the tufts and that both portions of the wefts behind the tuft yarns are pulled or closed up after said tuft yarns have been inserted.

- 10 No alteration is needed in the main cams whether the weave be two shot, three shot of four shot, and therefore any desired change from one weave to the other can be effected with the greatest ease.
- 15 I will refer hereinafter to the accompanying drawings, which illustrate diagrammatically an example of the present invention, only so much of an Axminster loom being shown as will suffice for my 20 purpose, the omitted features being commonly known in the art of tufted pile carpet weaving.

Figs. 1, 2 and 3 show diagrammatically in plan parts of the essential features of 25 the loom in the positions they occupy during three successive stages of part of an operation relating to the dividing or selecting of the wefts for a three shot weave, the warp threads being omitted for clearness.

30 Fig. 4 is a side view of the loom viewed from the needle side, showing the position or progress from Fig. 2 to Fig. 3, the comb being left out for the purpose of showing the weft positions more clearly.

Figs. 5 and 6 are two diagrams of a two shot weave carried out by my invention, the only difference in the second being that the tufts go through to the back of the 40 fabric.

Figs. 7 and 8 are two diagrams of a three shot weave, the second differing from the first only in the tufts extending through to the back.

45 Fig. 9 is a diagram of a four shot weave in which the tufts extend to the back.

Fig. 10 is a side view of the mechanism for producing the two shot weave shown in Fig. 5.

50 Fig. 11 is a similar view in relation to Fig. 6.

Figs. 12 and 13 are side views of the mechanism applicable to the weaves shown in Figs. 8 and 9 respectively.

55 All of these weaves, and others besides, can be made by suitably applying my present invention.

In the drawings, A represents the upper shuttle race, (the lower shuttle race with 60 another shuttle being immediately below it), N' the upper needle, N² the lower needle, T' T² the top weft, B' B² the bottom weft, W the woven fabric leading down to the spike roll, E the slay and C the comb. R is a retaining finger or

bolt adapted to slide backward and forward in guides G G upon the side J of the two shuttle races for the purpose fully explained below, and P and F are special placers or pushing fingers situated at either 70 side of the loom for the purpose of arranging the wefts for the insertion of the tufts according to the desired weave. Other mechanical details will be mentioned in the further description of the operation. 75

Referring to Figs. 1, 2, 3, and 4 in conjunction with Fig. 7, which illustrates my ordinary three shot weave, the upper needle N' carries two strands of weft simultaneously in its one eye, which for clearness is 80 shown as a single strand T' in Figs. 1 to 4, but is seen as a double strand (or two distinct strands) in the diagram of the weave in Fig. 7. The weft in the lower needle N², here being a single strand, is shown of larger substance in Fig. 3, although this difference in substance is optional. According to my method, the whole of the weft B' B² in the lower shed and the half T² of the weft T' T² in the upper shed is 90 moved forward to the fell of the fabric W. The tufts Y are inserted into the space V thus formed, that is to say, only the unmoved half T' of the top weft remains behind the tufts, which are eventually 95 doubled up around the latter T'.

Describing the operation in more detail, the wefts pull from the corner Z (Fig. 2) of the fabric around the end of the comb C when being inserted at the right hand side 100 of the loom.

The needles N' N² (mounted parallel upon one holder) are inserted and withdrawn (see Fig. 1) by the usual mechanism.

105 The top weft T' slips off the tail end of the shuttle H and (with the top selvage cord through it) gets caught and held by the retainer R, which for this purpose has slid meanwhile from the forward position shown in dotted lines in Fig. 2 to that shown in full lines, in both Figs. 2 and 4.

This backward position of the retainer R is also shown in Fig. 4, which will now be more fully described. The side framing 115 K of the loom carries fulcrum pivots X', F' and P' for three levers respectively, namely X, which is linked by a link R' to the retainer R, and the levers or placers P and F. These three levers X, P and F are 120 caused to sway to and fro, as desired, by reason of their lower ends being controlled by three cams, X², P², and F² mounted on a common shaft K'. There are other cams for operating the slay E, comb C, (Figs. 1, 2, 125 3), needles N', N², and other working parts which occupy the usual positions and therefore need not be described herein.

The bottom weft B' B² is caught by the bottom selvage cord S, (see Fig. 2) it being 130

unnecessary to employ any other retaining device for this.

The placer P (on shuttle side of loom) and F (on needle side) now come into operation, first P and then F.

The forward swing of P catches all the wefts (viz. T², B' B²) excepting the top half of the upper one (Figs. 2 and 4), leaving the latter half T' stretched across the 10 loom from the retainer R to the top needle N'.

In the enlarged Fig. 7, each half weft T' and T² is clearly shown as consisting of two strands, although the description or kind of 15 weave would be unaffected if only one such strand had been used, inasmuch as the two strands always remain as one undivided.

When the placer P has proceeded through the positions shown in Figs. 2 and 4 up to 20 the fell of the fabric W (which occupies only a moment of time), the other placer F swings forward, catching the other end of the bottom weft B' and moving it up to the fell, as shown in Fig. 3, at the same time 25 taking up the slack in the needle N². The tuft yarns are now inserted and the weft T' released from the retainer. The slay E then moves forward and bears against the fell while the tuft spool is rising to draw off 30 more length of tuft for the next insertion. When drawing off ceases by the spool coming to rest, the slay E goes back and the comb C advances and turns up the tuft 35 yarns, whereupon the cutting of the latter takes place.

After the tufts have been turned up, fresh 40 sheds are formed, wefts are inserted, and the order of placing and so on, as described above, is repeated for each successive row of tuft yarns.

Q is a fixed pin or guide roller around 45 which the top weft T² (also the two shuttle selavage cords) may pull, but the edge of the gap M in the shuttle races could be rounded 50 if desired and the pin or roller Q dispensed with.

In order to make a two or a four shot 55 weave (as in Figs. 5, 6 and 9), it is easy to adapt the placers and retainers, the latter being used on the needle side of the loom 60 also, but in no case need the number of needles be increased.

Referring to Fig. 10, which illustrates 55 mechanism for producing the two-shot weave shown diagrammatically in Fig. 5, no retainer R (Fig. 4) is required. As the needles pass into the sheds, the weft T² in the upper shed is caught by a rising finger on the needle side of the loom. Such finger 60 rises and falls, and similar fingers are so well known on Axminster looms, that it is thought unnecessary to show a drawing of it. (An example of one will be seen in Southwell and Head's Patent, No. 631,233, 65 reference I in Figs. 1, 2 and 6 of their speci-

fication). The weft B² in the lower shed becomes pulled around the comb C as shown in Fig. 2. When the needles have reached their farthest traverse, the shuttles enter the loops of wefts and the needles then 70 return leaving the wefts in the sheds as elongated loops. When these loops of weft have settled onto the shuttle threads S (Fig. 2), the placer P moves the portion of weft B² up to the fell, and as soon as the 75 needles are clear of the sheds, the placer F brings the portion B' also up to the fell. The tufts are then inserted, and the slay E (Fig. 4) brings up the loop of weft T' and T² from its rear position shown in Fig. 80 10 to the forward position shown in Fig. 5: After the beat up is finished, the slay swings back, the comb C turns up the tufts, and the warps L change positions ready for another 85 insertion of wefts, the placers F and P having also in the meantime moved to their rear positions through the action of the cams F² and P² respectively.

Referring to Fig. 11, which shows how 90 the two shot weave, Fig. 6, is made, the retainer R is preferably used for the bottom weft B' B² but is not indispensable. The weft T' and T² in the upper shed is pulled around the end of the comb C (Fig. 1) and the portion B² of the weft in the lower shed 95 is pulled against a finger (already described in connection with Fig. 10) during the insertion of the needles. After the shuttle cords S have passed through the loops, the placers P and F operate as before described, 100 the tufts are inserted and the weft B' B² in the bottom shed, after having been released by withdrawal of the retainer R (by cam X² Fig. 4) is brought forward by the slay E during the beat up. After this has been 105 completed, the slay moves toward the rear position, the comb C turns up the tufts around the wefts B' and B² and the warps L, then change positions for the next insertion. The three shot weave (Fig. 7) is 110 the same as described earlier in the specification, but in this diagram it is shown as made by threading needle N' (Figs. 1, 3 and 4) with two threads, instead of one.

The three shot weave (Fig. 8) is constructed by the mechanism illustrated in 115 Fig. 12, in which the retainer R operates in the weft in the upper shed. The portion of weft T² shown in Fig. 12 during the insertion of the needles, is first pulled against 120 the end of the comb C, and the other portion T' is held fast by the retainer R. The portion B² of the lower weft is pulled against the finger previously mentioned as being well known on Axminster looms. 125 After the shuttle threads S have been passed through the loops of the wefts, the placers P and F operate on the portion T² T' of loop in the upper shed, while the loop in the lower shed is retained by the shuttle 130

thread. The tufts are then inserted, the retainer R is withdrawn, liberating the portion T' T' of the loop. The slay E then brings this portion and also the loop consisting of B² and B' into the forward position. After the beating up by the slay has finished, and it has moved back toward its rear position, the comb C turns up the tufts around the weft B' B² in the lower shed, so giving the result shown in Fig. 8. Change of warp positions then take place.

In Fig. 13 is shown the mechanism for producing the four shot weave as in Fig. 9. This form requires two retainers R R, which are operated simultaneously by the one lever X (Fig. 4) which is used, whether the retainers or retainer be used in the upper or lower wefts, or both. The portions of wefts T' and B² both pull around the end of comb C during insertion, as shown in Fig. 1. The placer P on left side is the only one necessary for this weave and by preferably using the well-known slip eyed needle instead of the inclosed eyed pattern, the lower portion of the upper wefts and the upper portion of the lower wefts may be operated on by placer P as shown. The tufts are inserted, retainers R withdrawn, and the beat up of wefts and turning-up of tufts are done in the same order and method as previously stated for the other weaves.

The wefts in either needle for any of the weaves may be double as in top needle of weaves shown in Figs. 7, 8 and 9, and bottom needle of weave, (Fig. 9) or there may be only one thread in each needle as in weaves of Figs. 5 and 6 and the three shot weave shown on sheet.

For the purpose of a four shot weave for example (see Fig. 9), the placer F will be dispensed with, as the bottom weft B' B² will require to be split in addition to the top one as in the three shot weave. The placer P on the shuttle side of loom will also be modified, having provision for advancing only half of the bottom weft B' B² instead of the whole of the latter as before. An additional retainer will also be supplied for retaining the unmoved half of the bottom weft, such retainer being practically a duplicate of the retainer R.

It will be manifest that my present improvements can be applied to various weaves. I have given examples of two and three shot weaves in Figs. 6 and 8, the tufts going right through to the back of the fabric. Other examples will readily suggest themselves, it being a mere matter of controlling the particular wefts (or parts of weft) which are required. In all cases, the shedding movements are identical, the weft needles are inserted in the same position and intervals, and therefore the same cams can always be used; only the retaining means for the placing devices for the wefts

need slight variation, together with the tapers or the like which actuate them.

I claim:

1. In a loom for weaving tufted fabrics, means for inserting all the wefts necessary for one kind of weave simultaneously, a shuttle mechanism on one side of the loom for forming the selvage, a retainer finger located at the shuttle side of the loom for retaining a portion of the wefts and placer or pusher fingers for advancing the other part of the wefts toward the fell prior to beating up the wefts, the tufts being inserted in the space thus provided.

2. In a loom for weaving tufted fabrics, means for inserting all of the wefts necessary for one kind of weave simultaneously, a shuttle mechanism on one side of the loom for forming the selvage, means located at the shuttle side of the loom for retaining a portion of the wefts, and placer or pusher fingers operable successively for advancing the remaining portion of the wefts toward the fell, prior to beating up the wefts, the tufts being inserted in the space thus provided.

3. In a loom for weaving tufted fabrics, means for inserting all of the wefts necessary for one kind of weave simultaneously, a shuttle mechanism on one side of the loom for forming the selvage, means for dividing and retaining a portion of the wefts after same have glided off the end of the shuttle carrying the selvage cord, placer or pusher fingers for advancing the unretained portion of the wefts toward the fell prior to beating up the wefts, the tufts being inserted in the space thus provided.

4. In a loom for weaving tufted fabrics, means for inserting all of the wefts necessary for a weave simultaneously, a shuttle mechanism on one side of the loom for forming the selvage, means located at the shuttle side of the loom for retaining a portion of the wefts after the same have glided off the end of the shuttle and placer or pusher fingers located at opposite sides of the loom and operating successively for advancing the unretained portions of the wefts toward the fell prior to beating up the wefts, the tufts being inserted in the space thus provided.

5. In a loom for weaving tufted fabrics, means for inserting all of the wefts necessary for one kind of weave simultaneously, a shuttle mechanism on one side of the loom for forming the selvage, a reciprocatory finger or bolt located at the shuttle side of the loom at the gap of the shuttle race for retaining a portion of the wefts after the same have glided off the end of the shuttle, and means for advancing the remaining portion of the wefts toward the fell prior to beating up the wefts, the tufts being inserted in the space thus provided.

6. In a loom for weaving tufted fabrics, means for inserting all of the wefts necessary for one kind of weave simultaneously, a shuttle mechanism on one side of the loom 5 for forming the selvage, a reciprocatory finger or bolt located at the shuttle side of the loom at the gap of the shuttle race for retaining a portion of the wefts after the same have glided off the end of the shuttle, 10 and placer or pusher fingers located at opposite sides of the loom and operating successively for advancing the remaining portion of the wefts toward the fell prior to beating up the wefts, the tufts being inserted in the space thus provided.

ARTHUR DAVIS.
